UNITED STATES PATENT OFFICE.

ISIDORE CAVAZOS, OF KINGSVILLE, TEXAS.

ROTARY MOTOR.

Application filed August 24, 1925. Serial No. 52,019.

This invention relates to engines and has for its object the provision of a rotary engine capable of being operated by combustion, pressure and steam and designed to develop maximum power and efficiency.

The nature and advantages of the invention will be better understood when the following detailed description is read in connection with the accompanying drawings, the invention residing in the construction, combination and arrangement of parts as claimed.

In the drawings:

Figure 1 is an end elevation of the engine constructed in accordance with the present invention.

Figure 2 is a sectional view therethrough.

Figure 3 is a side elevation.

Figure 4 is an enlarged sectional view through the fuel inlet and the valve mechanism for controlling the admittance of fuel to the engine.

Figure 5 is a sectional view on line 5—5 of Figure 2.

Figure 6 is a longitudinal sectional view through an air inlet valve.

Referring to the drawing in detail, 10 indicates an engine casing of cylindrical contour in cross section, and supported upon a suitable base 11. If desired, this casing may be made in two parts bolted or otherwise secured together as at 12. Arranged within the casing 10 is a cam shaped member 13, and if desired this member may form an integral part of the casing without departing from the spirit of the invention. Mounted to rotate within the casing is a rotor 14 fixed upon a suitable shaft 15, and the rotor is provided with a plurality of pockets 16 in each of which is arranged a sliding piston 17. The pistons are normally influenced by springs 18 which tend to project the pistons outwardly beyond the periphery of the rotor, and into engagement with the wall of the casing 10 or the cam-shaped member 13. The rotor is, of course, eccentrically mounted and is adapted to contact the cam-shaped member 13 at one point as shown in Figure 2. It will also be noted that each piston 17 has its outer end rounded or curved to conform to the cam surface of the member 13, as this member is utilized to move the pistons within their pockets when they are brought into engagement therewith.

Arranged exteriorly of one end of the engine is a fuel pump 19 and an air pump 20,

these pumps being arranged at diametrically opposite points and operate to supply air and fuel to a pipe 21 which is threaded into the engine casing 10, communicating with a bore 22 formed in the casing and opening into a bore 23 formed in the cam-shaped member 13. The bore 23 is formed to provide a valve seat 24 which is normally engaged by a valve 25, the stem of which is indicated at 26 and arranged to slide in a passage 27. A valve operating rod 28 is terminally connected with the stem of the valve, and arranged longitudinally within the pipe 21, being pivoted therein at a point between its ends as at 29. The outer end of this operating element 28 is connected with a reciprocating rod 30 adapted to be actuated to control the movements of the valve 25 incident to the rotation of the rotor 14. In other words, the lower end of this rod 30 is connected with one end of an angularly shaped lever 31 pivoted at a point between its ends as at 32 upon a suitable bracket 33 arranged at one end of the engine, while the other end of the lever 31 carries a roller 34 which is adapted to cooperate with a cam 35 carried by the adjacent end of the rotor shaft 15. Consequently, as the shaft 15 rotates the lever 31 is intermittently locked upon its pivot in a direction to lower the operating element 38, the latter in turn closing the valve 25 against its seat 24. Now, when the roller 34 of the said lever 31 leaves the high point of the cam 35, the weight of the valve 25 is sufficient to allow the valve to gravitate to an open position, and thus admit a charge of fuel into the engine casing through the port 23. Leading from the fuel pump 19 is a pipe 36 which is connected to an elbow 37 attached to one end of the pipe 21, as shown in Figure 4, while leading from the air pump 20 is a supply pipe 38 which is terminally connected with a nipple 39 projecting from the end of the elbow 37, as illustrated. While any suitable means may be employed for operating the respective pumps, I preferably make use of a gear 40 which is carried by the rotary shaft 15, and which gear meshes with pinions 41 and 42, respectively. Each of these pinions is connected with the piston rod 43 of the adjacent pump, so that the said pumps are simultaneously operated incident to the rotation of the shaft 15, thus continuously supplying the pipe 21 with a charge of fuel. Of course, the fuel is in-

termittently admitted into the casing 10 of the engine to the valve 25 which is properly timed in the manner above described.

A spark plug 44 is supported by the casing 10 at a point adjacent the inlet port 23, while supported upon the casing in juxtaposition to the spark plug 44 is a valve casing 45. This casing establishes communication between the atmosphere and the interior of the casing 10, which communication is controlled by a ball valve 46, the valve in its entirety being utilized to prevent the formation of a vacuum within the engine casing, as will be readily appreciated. It will also be noted upon inspection of Figure 2 that I make use of a curved guide 47 against which the pistons 17 are adapted to be singly projected as they leave the cam surface of the member 17, thus guiding the piston into contact with the inner wall of the casing in a gradual manner, thus overcoming severe impacts between the piston and the casing 10. Carried by the cam-shaped member 13 is a resilient strip of any suitable material indicated at 49, the lower end of which is offset as at 50 to engage the adjacent end of the guide 47, thus sealing the cylinder at this point to prevent the escape or back pressure of the fuel when it is initially admitted into the cylinder 10. The structure in its entirety provides an engine which can be operated to produce a high degree of efficiency, and manifestly develop

maximum power with the consumption of a minimum amount of fuel.

35

While it is believed that from the foregoing description the nature and advantages of the invention will be readily apparent, I desire to have it understood that I do not limit myself to what is herein shown and described, and that such changes may be resorted to when desired as fall within the scope of what is claimed.

40

Having thus described the invention, what is claimed as new, is:—

45

The combination with an engine casing having a fuel inlet bore formed to provide a valve seat, of a fuel supply pipe threaded into the casing and communicating with said bore, a sliding valve normally engaging said seat and including a stem, said casing being recessed to receive said stem, a valve operating rod arranged within the supply pipe, and pivoted between its ends, and connected with said stem, a sliding rod operating through an opening in the supply pipe and connected with the adjacent end of the valve operating rod, a bracket, a rocking lever pivoted on said bracket and connected with said sliding rod, a rotary shaft, and a cam carried by the shaft for intermittently rocking said lever to open the valve, said valve gravitating to its closed position after each operation.

50

In testimony whereof I affix my signature.

REV. ISIDORE CAVAZOS.
